United States Patent Office.

JOSIAH J. FERRIS, OF PHILADELPHIA, PENNSYLVANIA, ASSIGNOR
TO HIMSELF AND MURPHY AND BROWN.

Design No. 3,587, dated July 27, 1869; antedated May 18, 1869.

DESIGN FOR A GATE.

The Schedule referred to in these Letters Patent and making part of the same.

To all whom it may concern:

Be it known that I, JOSIAH J. FERRIS, of Philadelphia, county of Philadelphia, State of Pennsylvania, have originated a new Design for a Gate; and I do hereby declare that the accompanying drawing, and following explanation thereof, form a full, clear, and exact description of the said design.

In the drawing, the figure represents a front view of the gate, which is edged by a plain beading, *a*, within which is a row of loop-like ornaments, *b*, and within this row of loops an oval scalloped rib, *c*.

The space between the rib *c* and the oval panel *d*, which forms the central figure of the design, is occupied by lattice-work composed of curved strips crossing

each other in the manner clearly represented in the drawing, and within the panel *d*, and radiating from a central ornament, *f*, of the same, is a number of curved arms, *h h*.

I claim the design for a gate, substantially as described, and as represented in and by the accompanying drawing.

In testimony whereof, I have signed my name to this specification, in the presence of two subscribing witnesses.

JOSIAH J. FERRIS.

Witnesses:

JOHN WHITE,
LOUIS BOSWELL.
